pany, Cleveland, Ohio, a corporation of Ohio

Application September 26, 1935, Serial No. 42,176

25 Claims. (Cl. 29—37)

This invention has to do with metal working machines such as automatic multiple and single spindle machines commonly known as automatic screw machines, the invention having particularly to do with what is designated herein as an automatic pick-up means, the object of the invention being to provide an improved means of this kind associated with the main tool slide of the machine and partly operated thereby during its advance movements.

A further object of the invention is the provision of an improved mechanism simple and efficient in operation and which may be used with an automatic multiple spindle machine having a main tool slide without in any way interfering with the operation of the machine and by means of which additional work may be performed and this during the ordinarily idle time of the machine whereby the cost of production is materially decreased in that the necessity of finishing the piece on a separate machine is avoided.

A further object of the invention is the provision of an improved pick-up attachment or mechanism particularly adapted for use with an automatic machine having a rotary work spindle and an axially supported tool slide shiftable toward and from that spindle and in which the pick-up attachment comprises a rotary work holder carried by the tool slide and longitudinally shiftable thereon independently thereof and rotated by the driving means for the rotary work spindle at the same speed and in the same direction as said spindle and in which the rotary work holder is shifted toward the work spindle, then partly backward therefrom, then toward the spindle and then backward by suitable cam means from the main cam shaft of the machine and which rotary work holder includes means for clamping the end of the work or stock rod carried by the rotary work spindle prior to the cutting off thereof and operated by the tool slide on the advance thereof, a transversely operative severing or cut-off means carried by a cross or transverse slide of the machine for cutting off the end of the stock rod carried by the work spindle after it is clamped by the rotary work holder and means for operating on the end of the cut-off piece after it is clamped by the work holder and after it is severed from the stock rod by the cut-off tool and which last means is brought into operation on the retractive movement of the cross slide for operation on the cut-off piece during the last forward movement of the work holder and in the preferred form thereof is so connected with the cross slide that the latter

on its retractive movement swings it into axial alignment with the rotary work holder for operating on the cut-off piece carried thereby.

A further object of the invention is the provision of an improved pick-up attachment employing a finishing tool brought into operative position during the retraction of the cutting off tool carried by a transverse cross slide of the machine.

A further object of the invention is the provision of an improved pick-up attachment in which a swinging finishing tool is connected with and is brought into operative position by a transverse or cross slide carrying a cut-off tool.

In the drawings accompanying and forming a part of this specification, Fig. 1 is a side view of this improved pick-up attachment and of the machine to which it is applied.

Fig. 2 is a cross-sectional view taken on the line 2—2 of Fig. 1, looking in the direction of the arrows.

Fig. 3 is a side view of the rotary pick-up work holder.

Fig. 4 is a cross section taken on the line 4—4 of Fig. 3.

Fig. 5 is a top view partly in section of this improved pick-up attachment.

Fig. 6 is a detailed perspective view of the slide for supporting the rotary work holder on the main tool slide.

Fig. 7 is a perspective view of the mechanism for longitudinally shifting this improved rotary work holder and rotating it.

Fig. 8 is a detailed perspective view of the trip mechanism operated by the main tool slide for operating the clamping means of the rotary work holder to clamp the work.

Fig. 9 is a detail perspective view of the transverse or cross slide carrying the severing tool and of the swinging finishing tool associated therewith and operated thereby.

Figs. 10 to 13 illustrate the operative positions of the rotary work holder and its associated finishing tool and cut-off tool during their several movements, and

Fig. 14 is a perspective view of a completed piece of work.

Similar characters of reference indicate corresponding parts in the several views.

Before explaining in detail the present improvement and mode of operation thereof, we desire to have it understood that the invention is not limited to the details of construction and arrangement of parts illustrated in the accompanying drawings since the invention is capable

of other embodiments, and that the phraseology which we employ is for the purpose of description and not of limitation.

While this improved pick-up attachment may be used with automatic machines having a single spindle and a shiftable tool slide, it is shown in the present instance embodied in an automatic multiple spindle machine having an indexable work spindle carrier 2 provided with a series of 10 rotary work spindles 3 rotated in the usual way from the main driving shaft 4 and which driving shaft passes axially through a main tool slide 5 axially supported relative to the work spindle carrier 2 and carrying the usual tools for working on the ends of the stock rods, this main tool slide being reciprocated by a cam drum mounted on the usual cam shaft of the machine.

Mounted on the main tool slide 5 is a supplemental or auxiliary slide 6 shiftable longitudinally on the main tool slide. Carried by this slide is a rotary pick-up work holder comprising a housing 7 having therein a rotary spindle 8 carrying a suitable collet or clamping or chucking mechanism 8' therein, all of which is similar in a general way to the rotary spindle mechanism of the indexable carrier and, therefore, requires no detailed description.

This rotary spindle 8 is rotated by a shaft 9 bolted to the end of the spindle and has a gear 10 splined thereon in mesh with a gear 11 carried by the main driving shaft 4 of the machine and, therefore, is rotated at the same speed and in the same direction as the rotary spindles of the indexable carrier.

35 The auxiliary slide 6 carrying this rotary work holder is shifted back and forth on the main tool slide by the mechanism shown in Fig. 7 comprising suitable cams 12 on a cam drum 12' mounted on the usual cam shaft of the machine 40 and link and rod mechanism 13 connected to an arm 14 adjustably connected to a rod 15 connected with an ear 16 of the housing 7 of the rotary work holder. The cams are so formed and positioned on the cam drum that, at the 45 proper time and when the indexable work spindle carrier has carried the work or stock rod into position to be severed by the severing tool, the rotary work holder will be shifted forward on the main tool slide to clamp the end of the 50 stock rod and when the end or piece of work has been cut off from the main stock rod, it will then be shifted backward part way to permit the finishing tool to be brought into axial alignment with the cut off piece of work at which time the 55 rotary work holder is again moved forward so that the finishing tool may properly perform its operation after which the rotary work holder is retracted to permit the completed piece of work to be ejected.

60 As before stated, the rotating spindle 8 of the auxiliary rotary work holder has suitable clamping or collet mechanism for clamping the end of the stock rod before it is severed from the main stock rod carried by the rotary work spindle and 65 this clamping mechanism is operated to clamp the work on the advancing movement of the tool slide 5. For that purpose, this tool slide 5 is provided with a suitable latch or trip 17 bolted to one face thereof and in position to engage 70 the sear 18 of a swinging finger 19 fixed to the housing 7 of the rotary work holder and this finger 19 operates the chuck spool shifting yoke 21 mounted on the rod 15 for actuating the spool 22 and thereby the collet in the usual way to 75 clamp it on to the work at the proper time,

The auxiliary slide 6 has a concaved or cut-out portion 23 to accommodate the grooved spool 22.

When the rotary work holder of the pick-up attachment is, by means of the cam mechanism hereinbefore referred to, shifted along the main tool slide and into position to contact with the end of the stock rod carried by the rotary work spindle, the main tool slide 5 during its advance movement carries the latch or trip 17 into position to contact with the sear 18 of the link 19. This link then pushes the yoke 21 and thereby the chuck spool 22 over the rocking fingers 25 (see Fig. 4), thereby oscillating them to push the conventional collet over its collet seat, thereby gripping the work so that when the cut-off tool 15 cuts the piece off from the bar stock, the piece of work is held securely in the collet of the pick-up attachment. At this time the rotary work holder of the pick-up attachment returns part way and thereupon the swinging finishing tool 20 is brought into position in axial alignment with the work to perform the secondary operation.

In this improved pick-up attachment, while the advancing movement of the main tool slide 5 operates through the trip mechanism 17, 18 and 19 to clamp the collet on to the end of the stock rod, the collet is released when the rotary work holder is fully retracted by some suitable means such as a fixed stud 24 on the machine frame which will operate the spool 22 in the opposite direction to release the collet from the work.

30 Mounted on the frame work or bed of the machine is the usual transverse or cross slide 30 carrying the cut-off or severing tool 31 for cutting off the end of the stock rod at the proper time, this slide being operated by suitable cams carried by a cam drum 30' mounted on a transverse shaft in the usual way and this slide is utilized to operate the swinging finishing tool although it may be independently operated if desired.

35 Bolted to this machine frame is a bracket 32 (see Fig. 2) and pivotally supported by this bracket is a swinging arm 33 to which is bolted a tool holder 34 carrying a finishing tool 35 of a form suitable for the work to be done, such as boring, drilling, facing, chamfering, reaming, counter-boring, etc. This arm 33 is connected with an ear 36 bolted to the cross slide 30 (see 40 Fig. 9) by means of a rod 37, one end of which is connected to the lower end of the swinging arm 33 (see Fig. 2) and on this rod is located a spring 38. Thus, during the forward movement of the cross slide 30 to carry the cut-off tool 31 (see 45 Fig. 5) into position to sever the piece of work from the stock rod, the swinging arm 33 and its tool 35 are swung away from the rotary work holder and as the cross slide 30 is retracted after the end of the stock rod is cut off, this swinging 50 arm 33 and its tool 35 are swung into operative position to bring the tool 35 in axial alignment with the work spindle 8 and the piece to be operated upon and at which time the auxiliary work holder has been partly shifted backward by the 55 cam mechanism hereinbefore described.

When the finishing tool is in position, the rotary work holder 8 is then shifted forward to have the end of the piece of work clamped thereby operated upon by the finishing tool 35 until this 60 secondary operation is completed. The rotary work holder 8 and its piece of work are then shifted to the rear or fully retracted by the cam mechanism and in position to have the piece of work ejected.

During this movement to the rear or all the way back, the chuck spool 22 is operated by the yoke 21 coming into engagement with the stop rod 24 (see Fig. 7), thereupon shifting the spool 5 to release the fingers 25 (see Fig. 4) and permit the collet to unclamp the piece of work and at this time it is ejected by suitable ejecting mechanism in the form of a spring pressed plunger or ejector 40 located inside the collet (see Fig. 4).
 10 The operation of the several elements of this improved pick-up attachment is illustrated in Figs. 10 to 13, in which it will be seen that, in Fig. 10, the rotary work holder carried by the auxiliary slide on the main tool slide has been moved forward by the cam mechanism to clamp the end of the stock rod and that the cutting-off tool 31 carried by the cross slide 30 has been shifted into position to cut off the end of the stock rod. At this time the finishing tool 35 is 20 swung out of position.

In Fig. 11, the piece of work having been clamped by the collet in the rotary work holder and cut off, has been shifted away from the main stock rod or work spindle and the finishing tool 25 35 has been swung into position in axial alignment with the piece of work while the cut-off tool 31 has been retracted.

In Fig. 12, the rotary work holder has been again shifted forward to bring the cut-off piece 30 of work into engagement with the cut-off tool 35 for the finishing operation.

In Fig. 13, the rotary work holder has been fully retracted from the finishing tool 35 and the piece 35 of work designated as W, Fig. 14, ejected therefrom.

Thus, it will be seen that after the forward end 40 of the stock bar carried by the rotary work spindle has been operated upon in the usual way, the opposite end thereof after it has been severed from the stock bar can be operated on by the tool 35 or any other suitable form of tool desired so that both ends of the work are completed on the same machine by a very simple pick-up attachment associated with the main tool slide and in which that main tool slide is operative to operate the collet to clamp the work.

Therefore, in this machine during the time that the main tool slide returns to its rear position to clear the tools from the work carried by the work 50 spindles and the spindle carrier indexes, the bar of stock is fed through a work spindle, chucked and the independent pick-up attachment is operated to clamp a piece of work which has been severed from the bar stock and moves this piece 55 of work toward the finishing tool 35 so that the entire secondary operation of this piece of work can be completed during the idle time of the machine without any loss of time and thus greatly reduces the cost of manufacturing the parts where 60 a secondary operation like drilling, counter-boring, reaming, slotting or other similar operations are necessary.

For instance, on a six spindle automatic machine, the stock is fed out on the first operation 65 in one of the rotary work spindles 3 of the indexable carrier 2; and the piece is rough formed and partly drilled by a drill mounted on the main tool slide. In the second operation, the work carrier having been indexed, this piece is finished 70 formed on the outside diameter and again partly drilled to two-thirds of its depth. On the third operation, the work carrier being again indexed, the outside diameter of the piece is shaved or scraped to hold the diameter to extreme accuracy and during this operation the piece is drilled the 75

full depth. In the fourth operation, with the carrier again indexed, the piece is tapped.

On the fifth indexing, the thread behind the hex shoulder is rolled by means of the threading rolls or exteriorly threaded or in some cases where 5 an external threading operation is required in front of the hex, this can be done with a threading die.

In the sixth operation the piece is cut off from the bar and during that operation this piece is 10 gripped by the pick-up attachment before it is severed from the bar and is then operated on in the manner hereinbefore described.

Thus, it will be seen that this improved pick-up attachment co-operates and is associated 15 with the main tool slide located and supported within the periphery of the work spindles, that is to say, the axially supported main tool slide slidingly supports this pick-up attachment in axial alignment with a rotary work spindle of 20 the work spindle carrier without any additional supporting means. By supporting the auxiliary slide on the main tool slide, this enables the auxiliary slide to be very rigidly supported close up to the work, thus avoiding any overhang of the 25 work or rotating spindle and thereby doing away with any chattering or vibration and insuring accuracy of the work and the utilization of the main tool slide to control the operation 30 of the clamping means of the pick-up attachment to clamp the work during the advance movement of the main tool slide permits the use of a simple tripping means to accomplish this purpose which would otherwise have to be 35 a complicated movement by means of cams, levers, etc., operating from the main cam shaft and involving considerably more mechanism and expense and since the main tool slide is always controlled in its forward and backward movement from the main cam shaft, exact timing of 40 the auxiliary pick-up is obtained while, as before stated, the auxiliary pick-up is always maintained in alignment with the work spindle.

It is to be understood that by describing in detail herein any particular form, structure or 45 arrangement, it is not intended to limit the invention beyond the terms of the several claims or the requirements of the prior art.

Having thus explained the nature of our said 50 invention and described a way of constructing and using the same, although without attempting to set forth all of the forms in which it may be made, or all of the modes of its use, we claim:

1. An automatic machine having a rotary work 55 spindle, main tool and auxiliary slides having relative longitudinal reciprocating movements, rotatable clamping means carried by the auxiliary slide and rotatable in the same direction and at the same speed as the rotary work spindle, cut-off means and finishing means operative in succession, and means operative by the main tool slide for controlling the clamping of the work by the clamping means carried by the auxiliary slide.

2. An automatic machine having a rotary work spindle, main tool and auxiliary slides having 60 relative longitudinal reciprocating movements, rotatable clamping means carried by the auxiliary slide and rotatable in the same direction and at the same speed as the rotary work spindle, cut-off means and finishing means operative in succession, and means operative by the main tool slide during the advance movement of the main tool slide for controlling the clamp- 65 70 75

ing of the work by the clamping means carried by the auxiliary slide.

3. An automatic machine having a rotary work spindle, main tool and auxiliary slides having relative longitudinal reciprocating movements, rotatable clamping means carried by the auxiliary slide and rotatable in the same direction and at the same speed as the rotary work spindle, cut-off means and finishing means operative in succession, means operative by the main tool slide for controlling the clamping of the work by the clamping means carried by the auxiliary slide, and a transverse slide, the successive operation of the cut-off and finishing tools being controlled by said transverse slide.

4. An automatic machine having a rotary work spindle, main tool and auxiliary slides having relative longitudinal reciprocating movements, rotatable clamping means carried by the auxiliary slide and rotatable in the same direction and at the same speed as the rotary work spindle, cut-off means and a swinging finishing means operative in succession, means operative by the main tool slide for controlling the clamping of the work by the clamping means carried by the auxiliary slide, and a transverse slide supporting said cut-off means and swinging finishing means, the successive operation of the cut-off and finishing tools being controlled by said transverse slide.

5. An automatic machine comprising a reciprocating tool slide, a rotary work spindle and a pick-up attachment comprising a reciprocating and rotary clamping means shiftable independently of the main tool slide and rotatable at the same speed and in the same direction as the rotary spindle, a severing means and a finishing means, the latter thrown into operation on the retraction of the former, and means operated by the main tool slide on the advance thereof for controlling the clamping of the work by the clamping means.

6. An automatic machine comprising a reciprocating tool slide, a rotary work spindle and a pick-up attachment comprising a reciprocating and rotary clamping means shiftable independently of the main tool slide and rotatable at the same speed and in the same direction as the rotary spindle, a severing means and a finishing means, the latter thrown into operation on the retraction of the former, means operated by the main tool slide on the advance thereof for controlling the clamping of the work by the clamping means, and means for ejecting the work on the release of the clamping means.

7. An automatic machine having an axially supported reciprocating main tool slide and a rotating work spindle, an auxiliary slide associated with and shiftable relative to said main tool slide, rotatable clamping means carried by said auxiliary slide and rotated at the same speed and in the same direction as the work spindle, means carried by the main tool slide for operating said clamping means to close it on to the work during the advance of the main tool slide, a transversely operating cut-off tool, and a transversely operating finishing tool.

8. An automatic machine having an axially supported reciprocating main tool slide and a rotating work spindle, an auxiliary slide associated with and shiftable relative to said main tool slide, rotatable clamping means carried by said auxiliary slide and rotated at the same speed and in the same direction as the work spindle, means carried by the main tool slide for operating said

clamping means to close it on to the work during the advance of the main tool slide, a transversely operating cut-off tool, and a transversely operating finishing tool operative into position to operate on the work clamped by the clamping means on the retraction of the cut-off tool.

9. An automatic machine having an axially supported reciprocating main tool slide and a rotating work spindle, an auxiliary slide associated with and shiftable relative to said main tool slide, rotatable clamping means carried by said auxiliary slide and rotated at the same speed and in the same direction as the work spindle, means carried by the main tool slide for operating said clamping means to close it on to the work during the advance of the main tool slide, a transversely operating slide, a cut-off tool carried thereby, and a swinging finishing tool swung into operative position on the retraction of said slide.

10. An automatic machine having an axially supported reciprocating main tool slide and a rotating work spindle, an auxiliary slide associated with and shiftable relative to said main tool slide, rotatable clamping means carried by said auxiliary slide and rotated at the same speed and in the same direction as the work spindle, means carried by the main tool slide for operating said clamping means to close it on to the work during the advance of the main tool slide, a transversely operative slide, a cut-off tool carried thereby, and a swinging finishing tool operatively connected with said slide and swung into operative position on the retraction of said slide.

11. An automatic machine having an axially supported reciprocating main tool slide and a rotating work spindle, an auxiliary slide associated with and shiftable relative to said main tool slide, rotatable clamping means carried by said auxiliary slide and rotated at the same speed and in the same direction as the work spindle, means carried by the main tool slide for operating said clamping means to close it on to the work during the advance of the main tool slide, a transversely operating cut-off tool, a transversely operating finishing tool, and means operative on the retraction of the auxiliary slide for releasing the clamping means.

12. In a machine of the class described having a rotatable work spindle and a reciprocating main tool slide shiftable toward and from said work spindle, the combination of an auxiliary slide associated with and movable independently of but in the same direction as the main tool slide, rotatable means carried by said auxiliary slide for clamping the end of the work carried by the rotatable work spindle and rotatable with and at the same speed and in the same direction as the rotatable work spindle, means for shifting said auxiliary slide toward the work spindle to clamp the work, then partly backward therefrom, then toward said spindle and then to fully retract it, means operative by the main tool slide on its advancing movement to clamp the rotatable means of the auxiliary slide on to the work, means operative to sever the work when it is clamped by said rotatable means, and means operative into position to operate on the piece of work after it is severed and during the second advance of said rotatable means toward the work spindle.

13. In a machine of the class described having a rotatable work spindle and a reciprocating main tool slide shiftable toward and from said work spindle, the combination of an auxiliary slide

associated with and movable independently of but in the same direction as the main tool slide, rotatable means carried by said auxiliary slide for clamping the end of the work carried by the 5 rotatable work spindle and rotatable with and at the same speed and in the same direction as the rotatable work spindle, means for shifting said auxiliary slide toward the work spindle to clamp the work, then partly backward therefrom, then 10 toward said spindle and then to fully retract it, means operative by the main tool slide on its advancing movement to clamp the rotatable means of the auxiliary slide on to the work, means operative to sever the work when it is clamped by 15 said rotatable means, and means operative into position to operate on the piece of work after it is severed and during the second advance of said rotatable means toward the work spindle and shiftable into operative position during the retraction of the severing tool. 20

14. In a machine of the class described having a rotatable work spindle and a reciprocating main tool slide shiftable toward and from said work spindle, the combination of an auxiliary 25 slide associated with and movable independently of but in the same direction as the main tool slide, rotatable means carried by said auxiliary slide for clamping the end of the work carried by the rotatable work spindle and rotatable with and at the same speed and in the same direction as the rotatable work spindle, means for shifting said auxiliary slide toward the work spindle to clamp the work, then partly backward therefrom, then toward said spindle and then to fully 30 retract it, means operative by the main tool slide on its advancing movement to clamp the rotatable means of the auxiliary slide on to the work, means operative to sever the work when it is clamped by said rotatable means, means operative into position to operate on the piece of work after it is severed and during the second advance of said rotatable means toward the work spindle, a slide carrying the severing means, and 35 swinging means for carrying the means operative into position to operate on the work after it is severed. 40

15. In a machine of the class described having a rotatable work spindle and a reciprocating main tool slide shiftable toward and from said work 50 spindle, the combination of an auxiliary slide associated with and movable independently of but in the same direction as the main tool slide, rotatable means carried by said auxiliary slide for clamping the end of the work carried by the rotatable work spindle and rotatable with and at the same speed and in the same direction as the rotatable work spindle, means for shifting said auxiliary slide toward the work spindle to clamp the work, then partly backward therefrom, 55 then toward said spindle and then to fully retract it, means operative by the main tool slide on its advancing movement to clamp the rotatable means of the auxiliary slide on to the work, means operative to sever the work when it is clamped by said rotatable means, means operative into position to operate on the piece of work after it is severed and during the second advance of said rotatable means toward the work spindle, a slide carrying the severing means, and 60 swinging means for carrying the means operative into position to operate on the work after it is severed, the said swinging means connected with said slide and swung into operative position on the retraction of the severing means slide. 70

16. In a machine of the class described hav-

ing a rotatable work spindle and an axially supported reciprocating main tool slide shiftable toward and from said work spindle, the combination of an auxiliary slide carried by and shiftable relative to said axially supported main tool slide, 5 rotatable means carried by said auxiliary slide for clamping the end of the work carried by the rotatable work spindle and rotatable with and at the same speed and in the same direction as the rotatable work spindle, means for shifting 10 said auxiliary slide toward the work spindle to clamp the work, then partly backward therefrom, then toward said spindle and then to fully retract it, means operative by the main tool slide on its advancing movement to clamp 15 the rotatable means of the auxiliary slide on to the work, means operative to sever the work when it is clamped by said rotatable means, and means operative into position to operate on the piece of work after it is severed and during the 20 second advance of said rotatable means toward the work spindle. 25

17. In a machine of the class described having a rotatable work spindle and a reciprocating main tool slide shiftable toward and from said work 30 spindle and a cam shaft, the combination of an auxiliary slide associated with and movable independently of but in the same direction as the main tool slide, rotatable means carried by said auxiliary slide for clamping the end of the work carried by the rotatable work spindle and rotatable with and at the same speed and in the same direction as the rotatable work spindle, means for shifting said auxiliary slide toward the work 35 spindle to clamp the work, then partly backward therefrom, then toward said spindle and then to fully retract it, means operative by the main tool slide on its advancing movement to clamp the rotatable means of the auxiliary slide on to the work, means operative to sever the work when 40 it is clamped by said rotatable means, means operative into position to operate on the piece of work after it is severed and during the second advance of said rotatable means toward the work 45 spindle, and cam mechanism carried by the cam shaft for shifting the auxiliary slide. 50

18. In a machine of the class described having a rotatable work spindle, a reciprocating main tool slide shiftable toward and from said work 55 spindle, a cam shaft and a main driving shaft for rotating the work spindle, the combination of an auxiliary slide associated with and movable independently of but in the same direction as the main tool slide, rotatable means carried by said auxiliary slide for clamping the end of the work carried by the rotatable work spindle and rotatable with and at the same speed and in the same direction as the rotatable work spindle, means for shifting said auxiliary slide toward the work 60 spindle to clamp the work, then partly backward therefrom, then toward said spindle and then to fully retract it, means operative by the main tool slide on its advancing movement to clamp the rotatable means of the auxiliary slide on to the work, means operative to sever the work when 65 it is clamped by said rotatable means, means operative into position to operate on the piece of work after it is severed and during the second advance of said rotatable means toward the work 70 spindle, cam mechanism carried by the cam shaft for shifting the auxiliary slide, and means connected with the main driving shaft for rotating said rotatable means carried by the auxiliary slide. 75

19. In a machine of the class described having 75

a rotatable work spindle and a reciprocating main tool slide, one shiftable toward and from the other, the combination of a work-pick-up means and means for operating it, a transversely operative slide, means carried thereby and operative to sever the work when it is clamped by said pick-up means, cam means for positively shifting the slide and its severing means forward and backward, and swinging means operative into position on the retraction of said slide to operate on the piece of work after it is severed.

20. An automatic machine having one or more rotary work spindles, a driving shaft for rotating said spindle or spindles, an axially supported main tool slide, an auxiliary slide associated therewith, said slides having relative longitudinal reciprocating movements toward and from the work spindle, cam mechanism for reciprocating said auxiliary slide relative to the main tool slide to successively advance it toward the work spindle and away therefrom, then toward the work spindle and then to fully retract it, rotatable clamping means carried by the auxiliary slide and rotatable in the same direction and at the same speed as the rotary work spindle and driven from said driving shaft, means carried by the main tool slide for operating the rotatable clamping means carried by the auxiliary slide on the advance of said main tool slide, means for releasing said clamping means, a transversely operating slide, cut-off means carried thereby, a swingingly supported finishing means operatively connected with said transverse slide, said cut-off means and finishing means operative in succession, the finishing means swung into operation on the retraction of the cut-off means, and means for ejecting the finished piece of work from the clamping means.

21. In a machine of the class described having a rotatable work spindle and a reciprocating main tool slide, one shiftable toward and from the other, the combination of a work pick-up means and means for operating it, a transversely operative slide, means carried thereby and operative to sever the work when it is clamped by said pick-up means, and swinging means operatively connected with the transverse slide and operative into position on the retraction of said slide to operate on the piece of work after it is severed.

22. An automatic machine having a rotary work spindle, a main tool slide, an auxiliary slide mounted on the main tool slide, said slides having relative longitudinal reciprocating movements, rotatable clamping means carried by the auxiliary slide and rotatable in the same direc-

tion and at the same speed as the rotary work spindle, means operative on the movement of the main tool slide for controlling the clamping of the work by said clamping means, and cut-off means and finishing means operative in succession.

23. An automatic machine having an indexible work spindle carrier provided with a plurality of rotatable work spindles, a reciprocating axially supported main tool slide adapted to carry tools co-operating with the work carried by the work spindles, an auxiliary slide supported by the main tool slide, said slides having relative longitudinal reciprocating movements, a rotatable clamping means carried by the auxiliary slide and supported in axial alignment with one of the work spindles and rotatable in the same direction and at the same speed as said rotary work spindle, cut-off means and finishing means operative in succession, and means operative by the main tool slide for controlling the clamping of the work by the clamping means carried by the auxiliary slide.

24. An automatic machine having an indexible work spindle carrier provided with a plurality of rotatable work spindles, a reciprocating main tool slide adapted to carry tools co-operating with the work carried by the work spindles, an auxiliary slide supported by the main tool slide, rotatable clamping means carried by said auxiliary slide and rotated at the same speed and in the same direction as said work spindles, means carried by the main tool slide for operating said clamping means to close it on to the work during the advance of the main tool slide, a transversely operating cut-off tool, and a transversely operating finishing tool operative into position to operate on the work clamped by the clamping means on the retraction of the cut-off tool.

25. An automatic machine having an indexible work spindle carrier provided with a plurality of rotatable work spindles, a reciprocating main tool slide adapted to carry tools co-operating with the work carried by the work spindles, an auxiliary slide supported by the main tool slide, a work pick-up means carried by said auxiliary slide and means for operating it, a transversely operative slide, means carried thereby and operative to sever the work when it is clamped by said pick-up means, and swinging means operative into position on the retraction of said transverse slide to operate on the piece of work after it is severed.
